(57) **CLAIM**

The ornamental design for a combined outlet for accepting multiple enlarged plugs and surge protector, as shown and described.

DESCRIPTION

FIG. 1 is a front elevational view of a combined outlet for accepting multiple enlarged plugs and surge protector showing my new design;

FIG. 2 is a top plan view;

FIG. 3 is a right hand side elevational view thereof, the opposite side being the mirror image of that shown;

FIG. 4 is a rear elevational view thereof;

FIG. 5 is a perspective view thereof;

FIG. 6 is a front elevational view of second embodiment of a combined outlet for accepting multiple enlarged plugs and surge protector embodying my new design;

FIG. 7 is a top plan view thereof;

FIG. 8 is a right hand side elevational view thereof, the opposite side being the mirror image of that shown;

FIG. 9 is a rear elevational view thereof;

FIG. 10 is a perspective view of a combined outlet for accepting multiple enlarged plugs and surge protector.

FIG. 11 is a front elevational view of a third embodiment of a combined outlet for accepting multiple enlarged plugs and surge protector embodying my new design.

FIG. 12 is a bottom plan view;

FIG. 13 is a right hand side elevational view thereof;

FIG. 14 is a rear elevational view thereof; and,

FIG. 15 is a perspective view thereof.

The broken line showing of the electrical cord is included for the purpose of illustrating environmental structure only and forms no part of the claimed design.
